Patented Sept. 20, 1921.

UNITED STATES PATENT OFFICE.

WILLIAM LEACH, OF MOOSE JAW, SASKATCHEWAN, CANADA.

TRAIN-STOPPING DEVICE.

1,391,328.

Specification of Letters Patent. Patented Sept. 20, 1921.

Application filed March 27, 1920. Serial No. 369,292.

To all whom it may concern:

Be it known that I, WILLIAM LEACH, a subject of the King of Great Britain, and resident of Moose Jaw, in the Province of 5 Saskatchewan, Dominion of Canada, have invented certain new and useful Improvements in Train-Stopping Devices, of which the following is a specification.

This invention relates to improvements in 10 train stopping device, and the objects of the invention are to provide a simple and effective device which will make it possible for a train man or signal man outside of the train on the ground to stop the trains in 15 motion if from any cause the engineer has not seen him, whereby accidents due to oversight in this respect may be avoided.

Further objects are to provide such a device as may be operated from either side of 20 a train irrespective of the direction in which the train is going.

Further objects still are generally to simplify and improve the construction of the device to better adapt it to perform the 25 functions required of it.

It consists essentially of the improved construction hereinafter described in detail in the accompanying specification and drawings.

30 In the drawings:—

Figure 1 is a sectional elevation of a car with my invention applied thereto.

Fig. 2 is a sectional elevation of an alternative form of the invention.

35 Fig. 3 is a plan view of another embodiment of the invention, parts of the mechanism being omitted.

Fig. 4 is an elevation of the same embodiment as Fig. 3, showing the above omitted 40 mechanism.

Fig. 5 is a sectional detail through the signaling members used in the form shown in Fig. 1.

Fig. 6 is a sectional detail through the 45 valve used in the form shown in Fig. 2.

In the drawings, like characters of reference indicate corresponding parts in all the figures.

Referring first to the form shown in Figs. 50 1 and 5, A indicates a car having the usual train line pipes B beneath the same, which is in accordance with the invention connected to lateral branches 10 and 11, conveniently formed with check valves 12 and 13 and terminating in downwardly depending signal members C and D, these signal members ex-

tending at the side of the car beneath the bottom thereof in such a position that they may be readily struck by a train man or signal man on the ground outside the car. 60

The signal members C and D each comprise a frangible member 14 conveniently in the form of a glass tube having one end sealed, the upper end of which is received in a socket 15, of any convenient character, 65 connected to the end of the branch 10, the socket illustrated having a retaining nut 16 formed with a flange 17 tapered to embrace a corresponding flange on the member 14, the nut 16 having screw threaded engagement with the base portion 18 of the socket. 70

If desired for passenger cars, an incandescent lamp 14^a may be provided on the interior of the member 14.

In this form of the invention when it is 75 desired to stop the train, the signal man strikes and breaks the members C or D, which permits the air to escape from the train line pipes through the branch 10 and 11 which will apply the brakes.

It may also be caused by well known means to actuate the whistle or other signal.

In the alternative form shown in Figs. 2 and 6, the branches 10 and 11 terminate on opposite ends of the check valves 19, controlled by bearing levers 20, the control being such that when the lever 20 is swung in either direction, from its normal vertical position, air will be permitted to escape; thus for instance the plug 21 on the valve 85 may be formed with a central passageway 22 adapted when the lever is in either of the positions shown in dotted lines in Fig. 6 to register with outlet ports 23 and 24 in the casing 25. 90

It may also be found desirable to retain the lever in this inclined position, and for this purpose I provide a spring retaining member 26 adapted to receive and engage a projection 27 on the extended end of the lever 20, designed to retain a lever in either of its dotted line positions. 95

It will be seen that in this form of the invention, a train may be stopped by striking the lever moving it to its dotted line position. This operation may be caused to take place irrespective of the direction in which the train moves.

In the alternative form shown in Fig. 3, the train line pipe is connected to a central 110 valve 28 which is provided with an operating rod 29 which extends transversely fully

across the bottom of the car, and is formed with downwardly projecting depending ends 30 adapted to be engaged by the signal man. The construction of the valve 20 is such that when the valve is swung to either of its dotted line positions, the train line pipes will be opened, which may be accomplished for instance by connecting the plug 31 of the valve to the rod 28 causing the opening in the plug to register with ports 32 and 33 when the rod is in the dotted line positions.

10 The alternative form shown in Fig. 4 shows a further addition to the form shown in Fig. 3, whereby the movement of the rod 29 may be caused to operate the usual conductor's valve 34 in the car, this being accomplished by providing a lever 35 on the conductor's valve connected with a link 36, 20 which is pivoted to one arm of the bell crank 37, the other arm 38 is bifurcated, and adapted to engage the opposite sides of the rod 29, so that when the rod 29 is swung from one side to the other, it will swing the bell crank 37 and operate the conductor's valve, the bell crank 37 being suitably pivoted to a bracket 39 on the underside of the car.

15 It will be seen that in all forms of the invention, positive means are provided by which the signal man may stop the train and thus avoid accidents and the destruction of life and property through rear end collisions.

20 35 As many changes could be made in the above construction, and many apparently widely different embodiments of my invention, within the scope of the claims, constructed without departing from the spirit 40 or scope thereof, it is intended that all mat-

ter contained in the accompanying specification and drawings shall be interpreted as illustrative and not in a limiting sense.

What I claim as my invention is:

1. In a train stopping device, the combination of a car, a train line pipe beneath the car, a valve provided with two outlet ports, a lever adapted to operate the valve and cause it to register with either of the ports, said lever being operable by a stationary signal man, located at the side of the car when the car is moving in either direction.

2. In a train stopping device, the combination of a car, a train line pipe beneath the car, a valve provided with two outlet ports, said valve being centrally located, and lever means for operating the valve comprising a rod extending transversely across the car beneath the bottom of the same, and having depending ends adapted to be operated by a stationary signal man when the car is moving in either direction.

3. In a train stopping device, the combination of a car, a train line pipe beneath the car, a valve provided with two outlet ports, a lever adapted to operate the valve and cause it to register with either of the ports, said lever being operable by a stationary signal man, located at the side of the car when the car is moving in either direction, a conductor's valve and means for connecting the lever to the conductor's valve.

In witness whereof I have hereunto set my hand in the presence of two witnesses.

WILLIAM LEACH.

Witnesses:

J. H. HOWARD,
F. A. BOHNE.
